UNITED STATES PATENT OFFICE.

LOUIS L. GORR, OF MARSHFIELD, OREGON.

DOWNDRAFT-HEATER.

1,356,138.

Specification of Letters Patent. Patented Oct. 19, 1920.

Application filed February 17, 1917. Serial No. 149,225.

To all whom it may concern:

Be it known that I, LOUIS L. GORR, a citizen of the United States, residing at Marshfield, in the county of Coos and State of Oregon, have invented certain new and useful Improvements in Downdraft-Heaters; and I do hereby declare the following to be a full, clear, and exact description of the invention, such as will enable others skilled in the art to which it appertains to make and use the same.

The invention relates to improvements in down draft heaters.

The object of the present invention is to improve the construction of down draft heaters and to provide a simple, practical and efficient down draft heater of comparatively inexpensive construction equipped with means for enabling it to be converted in an up draft heater when it is desired to arrange the heater in this manner for starting a fire or for producing exterior heat, and capable of burning soft coal practically smokelessly or gaseous fuel with a minimum amount of air for supporting the combustion incident to the burning of such fuel.

A further object of the invention is to provide a down draft heater of this character adapted to heat the fuel air prior to introducing the same into the combustion chamber.

It is also an object of the invention to provide a heater for heating a fluid such as water, air or steam and arranged to introduce the heated medium into it at the point where the practically spent gases and other products of combustion leave the heater and at the same time to cause the heated medium to leave the heater as it passes through the hottest zone in the combustion chamber.

With these and other objects in view, the invention consists in the construction and novel combination of parts hereinafter fully described, illustrated in the accompanying drawings, and pointed out in the claims hereto appended; it being understood that various changes in the form, proportion, size and minor details of construction within the scope of the claims, may be resorted to without departing from the spirit or sacrificing any of the advantages of the invention.

In the drawings—

Figure 1 is a vertical longitudinal sectional view of a down draft heater constructed in accordance with this invention,

Fig. 2 is a transverse sectional view on the line 2—2 of Fig. 1,

Fig. 3 is a horizontal sectional view on line 3—3 of Fig. 1,

Fig. 4 is a horizontal sectional view on line 4—4 of Fig. 1,

Fig. 5 is a perspective view of the hollow grate,

Fig. 6 is a perspective view of a hollow grate designed particularly for heating air,

Fig. 7 is a vertical longitudinal sectional view of the hollow grate shown in Fig. 6.

Like numerals of reference designate corresponding parts in the several figures of the drawings.

In the accompanying drawings in which is illustrated the preferred embodiment of the invention the down draft heater illustrated in Figs. 1 to 5 inclusive comprises in its construction, a hollow grate 1 composed of separate sections preferably consisting of castings arranged side by side and adapted to be used in any desired number to provide a grate of the desired width and the said down draft heater is adapted to be constructed and operated in various sizes as it may be employed in an ordinary domestic heater or in a municipal garbage incinerating furnace. The hollow grate is composed of a front horizontal portion or grate bar 2, an upper transversely disposed vertically projecting arm or water back member 3, a depending transversely disposed flange 4 and a rearwardly projecting vertically arranged arm or member 5. The front portions 2 of the sections of the grate may be provided with laterally projecting lugs 6 and they are hollow and communicate with the arms 3 and 5 which are also hollow. The arms or members 3 of the sections of the grate are fitted together at their side faces or walls to form a continuous upwardly projecting transversely disposed water back or rear wall or partition. The depending flanges 4 which also fit against each other provide a depending transversely disposed partition or bridge wall and the rearwardly extending arms or members 5 which are also hollow are arranged in spaced relation and form narrow vertical chambers and provide intervening flues or spaces 7 for the passage of the products of combustion as hereinafter fully explained. The extensions 4^a on the lower ends of the members 3 fit against each other to provide a rearwardly directed deflecting

wall at the upper front ends of the flues 7. The rearwardly extending hollow members 5 are connected at their lower ends by substantially oblong coupling boxes or casings 8 fitted together at their ends as clearly illustrated in Figs. 4 and 5 of the drawings and provided with end and rear openings 9 and 10. The ends of the boxes or casings 8 fit flat against one another and they may be connected by press or inserted nipples 11 and they communicate at their rear openings 10 with a header 12 by short pipes or fittings 13. An inlet pipe 14 is connected with the header for introducing water or fluid medium in the heater. The medium to be heated enters the chamber 15 of the rearwardly projecting arm or member 5 and passes upwardly and forwardly through a lower duct or passage 16 in the front hollow grate portion 2 which is provided with a horizontal partition 17 extending forwardly from the rear end of the hollow front portion 2 and terminating short of the front end thereof and dividing the space within the said front portion 2 into a lower duct or passage 16 and an upper duct or passage 18. The heating medium passes around the front end of the horizontal partition 17 and enters the upper duct or passage of the front grate portion 2 and then passes into the chamber 19 of the upper transversely disposed hollow arm or member 3. The upwardly projecting arms or members 3 are provided with lateral openings 20 and top openings 21 and the interior chambers 19 communicate with one another through the lateral openings 20 in which are preferably arranged nipples 11 similar to those heretofore described. The said chambers 19 are also designed to be connected at the top with a manifold or header 22 by nipples or fittings 23 and an outlet pipe 24 extends from the manifold or heater 22 for conveying the heated medium to the desired point or points. The hollow grate is arranged within a casing which may consist of metal, masonry or any other suitable material according to the character of the heater in which the hollow grate structure is employed and the said casing is divided by the hollow grate structure into an upper combustion or fuel chamber 24, a lower ash pit or chamber 25 and a rear heating chamber 26 into which the rearwardly projecting arms or members 5 extend and divide the lower portion of such chamber into separate passages which are coincident with the intervening recesses 7 heretofore described. The upwardly projecting arms or members 3 form the rear wall of the combustion chamber and they terminate short of the top wall of the casing to provide an intervening space at which is located a transversely disposed damper 27. The depending flanges 4 form the rear wall 65 of the lower front ash pit or chamber 25 and

terminate short of the bottom of the casing to provide an intervening space at which is located a lower damper 28. The upper and lower dampers are adapted to be arranged as hereinafter fully explained to convert the 70 heater into either a down draft heater or an up draft heater.

The air for the supporting of combustion within the fuel chamber, when the heater is employed as a down draft heater, is introduced into the upper fuel chamber or combustion chamber 24 by an air duct 29 comprising a lower rear horizontally disposed inlet portion 30, an intermediate vertical connecting portion 31, an upper horizontally 75 disposed portion 32 and a front transversely disposed portion 33. The air is heated throughout its passage through the inlet flue and it is introduced into the combustion chamber 24 in a heated condition and is drawn downwardly through the fuel by the draft of a flue 34 and it passes through the lower chamber or ash pit 25. The gases and other products of combustion pass rearwardly through the damper controlled space 80 35 upwardly through the rear passages or spaces 7 into the rear heating chamber 26 and escape through the flue 34 which is provided with a damper 36. The vertical connecting portion 31 of the inlet flue is located 85 in the rear chamber 26 directly below the flue or smoke pipe 34 so that it is subjected to the practically spent gases and other products of combustion before the same escape to the chimney or flue and the air entering the duct 29 is heated in its passage through the same. The heated medium traveling through the hollow grate structure enters at the rear and is first subjected to the action of the gases and other products of 90 combustion escaping to the rear heating chamber 26 and is preliminarily heated before entering the front portion of the hollow grate and in its passage through the front hollow grate portion 2, the heating 95 medium is subjected to the hottest zone of the heater preparatory to its leaving the heater through the intensely heated upper chambers 19. The front face of the wall formed by the arms or members 3 may be 100 lined with fire brick when it is not desired to subject the heated medium to the intense heat at the rear wall of the combustion chamber. By this construction and arrangement of the hollow grate, the heated medium 105 is subjected to the most intense heat as it leaves the heater. The down draft is adapted to enable the fuel to be burned with the least amount of fuel air to support combustion and the air is heated prior to its introduction into the combustion chamber so that the temperature of the interior of the heater is reduced only to a minimum degree by the introduction of the said air.

The casing is provided with suitable doors 110

and when starting a fire or for any other reason it is desired to convert the heater into an up draft heater the lower damper 28 is closed and the upper damper 27 is opened 5 and air is admitted to the heater at the front of the lower or ash chamber or pit 25 through the door 37. This will cause the air to pass upward through the fuel and escape from the combustion chamber at the 10 back thereof over the rear wall formed by the arms or members 3, the gases and products of combustion passing directly to the stove pipe or flue 34.

When the down draft is employed for 15 heating air or water, the hollow grate may be constructed of sheet metal sections 49 which are shown in Figs. 6 and 7 of the drawings and which are preferably composed of similar opposite longitudinal sections or members 50 suitably secured together and forming a front portion 51 and an upwardly projecting transversely disposed arm or member 52 and a rearwardly projecting vertically disposed arm or member 53. 20 The front portion 51 is provided with a horizontal partition 54 and the rearwardly projecting portion or member 53 has a plurality of baffle plates or partitions 55. An inlet 56 is provided at the top of the rearwardly projecting portion 53 and an outlet 57 is arranged at the top of the transversely disposed upwardly projecting arm or member 52.

The down draft fluid heater is adapted 35 to burn soft coal smokelessly and also to burn gas in a burner. The soft coal is burned with the least possible amount of fuel air and the heating surfaces are arranged so that a maximum amount of the 40 heat resulting from the combustion of the fuel is absorbed by the heated medium and thus successfully utilized. This design lends itself readily to its adoption as a steam generator, a liquid heater or an air heater and 45 its range of construction will vary from the smallest domestic heater to that of the largest municipal garbage incinerator. The economy of the heater is assured since both the heating medium and the heated medium 50 travel in the most approved manner, inasmuch as the spent gases leave the heater where the heated medium enters and the heated medium leaves the heater as it passes through the hottest zone in the combustion chamber. The design illustrated in the 55 drawings reduces the material to a minimum and lessens the cost of production. The dimensions and proportions will be varied to suit the conditions and requirements and steam drums, expansion tanks 60 and various other accessories will of course be employed to make an installation a complete and practical heating apparatus. The heater is adapted to be readily arranged as 65 an up draft heater, the heater being re-

versed when starting a fresh fire or when heat is wanted outside of the heater or when it is necessary to use the heater primarily as a refuse burner.

The upper damper 27, which is preferably 70 located below the smoke pipe or flue 34, operates within an opening 62 from which the smoke pipe or flue 34 extends, and it is adapted to swing from the front wall to the rear wall of the said opening 62 in converting the stove or heater from a down draft to an up draft and it constitutes a two ported damper and may be swung from either of its 75 positions by any suitable operating mechanism such as a simple operating rod. 80 When the damper 27 is in one position it is entirely open and in the other position is entirely closed and it permits an up draft or a down draft arrangement to be instantly brought into operation. 85

The hollow heating element, which divides the casing of the stove into its several compartments and which is composed of the substantially horizontal front portion, the upwardly extending arm or portion and the rearwardly extending arm or portion, may have the upwardly and rearwardly extending arms or portions arranged in a variety of positions and the upwardly extending arm or portion, instead of being arranged at 95 the back of the combustion chamber to form the rear wall thereof, may be placed at one or both sides or in any other desired position, as will be readily understood, and, as illustrated in Figs. 6 and 7, the rearwardly 100 extending arm or portion, when disposed in an upwardly projecting position, will be arranged in spaced relation with the upwardly projecting transversely disposed portion 51 so that the highly heated air or 105 water passing out through the portion 51 will not give up any of its heat to the incoming water or air. This form of the invention may be advantageously employed as a water heater, and by arranging the said 110 portions of the hollow heating element in such spaced relation, the outgoing air or water is maintained at a maximum temperature.

What is claimed is:—

1. A heater of the class described including a casing, substantially horizontal members of hollow formation having upper and lower passages communicating at their front ends, upwardly extending members of hollow formation located at the rear ends of said horizontal members and communicating with the rear ends of said upper passages, the lateral sides of said upwardly extending members being arranged in abutting engagement, rearwardly extending members of hollow formation communicating with the rear ends of said lower passages, said rearwardly extending members being of less width than the upwardly extending members and rela- 115 120 125 130

tively spaced, bridge wall sections depending from the rear ends of said horizontal members and having their lateral sides arranged in abutting engagement, a supply pipe communicating with said rearwardly extending members, and a discharge pipe communicating with said upwardly extending members.

2. A heater of the class described including a casing, substantially horizontal members of hollow formation having upper and lower passages communicating at their front ends, upwardly extending members of hollow formation located at the rear ends of said horizontal members and communicating with the rear ends of said upper passages, said upwardly extending members communicating with each other at their upper ends and having their lateral sides arranged in abutting engagement, downwardly and rearwardly extending members of hollow formation communicating with the rear ends of said lower passages, said downwardly and rearwardly extending members being of less width than the upwardly extending members and relatively spaced, downwardly extending bridge wall sections located at the rear ends of said horizontal members, couplings carried by the lower rear ends of said downwardly and rearwardly extending members, said couplings being arranged in abutting engagement and communicating with each other and with said downwardly and rearwardly extending members, a supply pipe communicating with said downwardly and rearwardly extending members, and a discharge pipe communicating with said upwardly extending members.

3. A heater of the class described including a casing, substantially horizontal members of hollow formation having upper and lower passages communicating at their front ends, upwardly extending members of hollow formation located at the rear ends of said horizontal members and communicating with the rear ends of said upper passages, said upwardly extending members having their lateral sides arranged in abutting engagement with each other and with the sides of said casing, rearwardly extending members of hollow formation communicating with the rear ends of said lower passages, downwardly extending abutting bridge wall sections at the rear ends of said horizontal members, said bridge wall sections also abutting the sides of the casing, a supply pipe communicating with said rearwardly extending members, and a discharge pipe communicating with said upwardly extending members.

4. A heater of the class described including a casing, substantially horizontal members of hollow formation having upper and lower passages communicating at their front ends, upwardly extending members of hol-

low formation located at the rear ends of said horizontal members and communicating with the rear ends of said upper passages, the lateral sides of said upwardly extending members being arranged in abutting engagement with each other and the sides of the casing, rearwardly extending members of hollow formation communicating with the rear ends of said lower passages, said rearwardly extending members being of less width than the upwardly extending members and relatively spaced, bridge wall sections depending from the rear ends of said horizontal members and having their lateral sides arranged in abutting engagement with each other and the sides of the casing, a supply pipe communicating with said rearwardly extending members, and a discharge pipe communicating with said upwardly extending members.

5. A heater of the class described including a casing, grate bars provided with upper and lower passages communicating at their front ends, a water back communicating with the rear ends of the upper passages, a bridge wall depending from the rear ends of the grate bars, chambers projecting rearwardly beyond said water back and bridge wall and communicating with the rear ends of said lower passages, said chambers being arranged in relatively spaced relation to provide passages therebetween for the products of combustion, a supply pipe communicating with said chambers, and a discharge pipe communicating with said water back.

6. A heater of the class described, comprising a casing, grate bars provided with upper and lower passages communicating at their front ends, a water back communicating with the rear ends of the upper passages, a bridge wall extending downwardly from the grate bars, a deflecting wall extending rearwardly from the lower end of the water back, and chambers communicating with the rear ends of said lower passages and extending rearwardly beyond the water back, the bridge wall, and the deflecting wall, said chambers being relatively spaced to provide passages therebetween for the products of combustion, a supply pipe communicating with said chambers, and a discharge pipe communicating with said water back.

7. A heater of the class described comprising a casing, grate bars provided with upper and lower passages communicating at their front ends, a water back communicating with the rear ends of the upper passages and having its lateral sides arranged in engagement with the side walls of the casing, the upper end of the water back terminating short of the upper wall of the casing, a damper located between the upper end of the water back and the upper wall of the casing, a bridge wall depending from the

5 rear ends of the grate bars and terminating short of the bottom wall of the casing, a
casing, a plurality of chambers communicating with the rear ends of said lower
5 passages and located in rear of said bridge wall, said chambers being relatively spaced
to provide passages therebetween for the
10 products of combustion, a supply pipe communicating with said chambers and a discharge pipe communicating with said water back.

8. A heater of the class described comprising a casing, grate bars having upper and lower passages communicating at their front ends, upwardly extending members of hollow formation located at the rear ends of said grate bars and communicating with
20 the rear ends of said upper passages, said

members having their lateral sides arranged in abutting engagement to provide a water back, bridge wall sections depending from the rear ends of said grate bars and having their lateral sides arranged in abutting engagement, chambers communicating with the rear ends of said lower passages and arranged in relatively spaced relation to provide passages therebetween for the products of combustion, said chambers being 25 located in rear of said bridge wall sections, a supply pipe communicating with said chambers, and a discharge pipe communicating with said water back members.

In testimony whereof I affix my signature 30
in presence of two witnesses.
